UNITED STATES PATENT OFFICE.

ISAAC BERNAT, CARL ROSS, AND ADOLF BERNAT, OF KANSAS CITY, MISSOURI.

SHOE.

964,482.

Specification of Letters Patent. Patented July 19, 1910.

Application filed May 29, 1909. Serial No. 499,138.

To all whom it may concern:

Be it known that we, ISAAC BERNAT, CARL ROSS, and ADOLF BERNAT, citizens of the United States, residing at Kansas City, in the county of Jackson and State of Missouri, have invented certain new and useful Improvements in Shoes, of which the following is a specification.

Our invention relates to improvements in 10 shoes.

The object of our invention is to provide in a shoe a novel, resilient, foot support which will enable the wearer of the shoe to walk easily and with a springy step.

15 A further object of our invention is to provide a bellows-like foot support, provided with means by which, during the operation of walking, the air within a shoe containing the support may be kept in constant circulation, thereby facilitating evaporation and 20 adding to the comfort of the wearer of the shoe.

Other novel features are hereinafter fully described and claimed.

25 In the accompanying drawings which illustrate the preferred form of our invention, Figure 1 is a view, partly in elevation and partly in central vertical section, of a shoe provided with our improved foot support.

30 Fig. 2 is a bottom view, with the lower half of the sole and the heel removed. Fig. 3 is a top view, with the upper removed.

Similar characters of reference denote similar parts.

35 1 denotes an ordinary shoe, having a sole 2 and the heel 3. A resilient support for the foot, is mounted on the sole 2 above the heel 3. This foot support comprises preferably a bellows-like air pump, which is compressible by the weight of the person's foot and is 40 preferably provided with resilient means for resisting such compression. The bellows-like support is preferably provided with means for taking air from and projecting it into the interior of the shoe for the purpose of causing a circulation of air within the shoe.

In the preferred form of our invention, the bellows-like support is provided with a 45 cup-shaped base 4, located in a recess provided in the upper side of the sole 2, preferably above the heel 3. Above the base 4 is a foot support comprising a horizontal plate 5, which is preferably supported upon the upper end of a coil spring 6, the lower end of which is supported upon the upper

side of the bottom of the cup-shaped member or base 4. The lower end of the spring 6 is provided with a projection 6', which extends vertically downward through an opening 7 provided therefore in the bottom of the base 4, the projection 6' being turned laterally below the base 4, as shown in Fig. 2.

A flexible, tubular, air-tight member 8; which may be composed of any suitable material, such as soft rubber, oil cloth or plain canvas, is secured at its upper end to the foot support 5. The lower end of the member 8 is preferably detachably secured to the base 4, by means of two concentric rings 9 and 10, between which the tubular member 8 is tightly clamped, the ring 10 being internally screw threaded and fitted to the externally threaded periphery of the circular upper end of the base 4. By providing a resilient tubular member 8, composed of such material as soft rubber, the spring 6, if desired, may be dispensed with. By having the member 8 detachable from the base 4, said member may be removed for any desired purpose. For example to replace the spring 6 or to close the air conductor 11, in case, as in winter time, it may be desired to dispense with the air currents, and employ the mechanism solely as a resilient foot support.

A further object in having the foot support 5 and flexible member 8 detachable, is to permit their removal and that of the spring 6 when the heel is compressed in the finishing of the shoe, or when it is desired to hammer the heel without injury to the spring or foot support.

The base 4 is provided with one or more nozzles or air conductors 11, which are preferably embedded in the sole 2, and are respectively provided with outer open ends 12 which communicate with the interior of the shoe, above the sole 2. The openings 12 may be disposed wherever it may be desired. In the drawings three such openings are shown, two being located near the toe of the shoe and one near the middle thereof.

In the operation of our invention, the weight of the foot moves the foot support 5 downwardly, such movement being resisted by the spring 6, which, when the weight is removed, restores the foot support 5, to the elevated position shown in Fig. 1. When the support 5 is depressed the air is expelled from the bellows-like support into the interior of the shoe through the nozzles or

conductors 11. When the spring 6 raises the support 5 the air is drawn from the interior of the shoe through the said conductors or nozzles, into the bellows-like receiver. By this means, during walking the air in the shoe will be kept in constant circulation, thus facilitating the evaporation of moisture and producing a cooling effect upon the foot of the person wearing the shoe.

By reason of the resiliency of the bellows-like support, the person wearing the shoe will be enabled to walk easily and with a sprung step, and the shocks produced by the striking of the heel of the shoe upon hard ground or pavement, will be absorbed and will not affect the person. By having the conductors terminating at their intake and discharge end, above the sole of the shoe and in communication with the interior thereof, there is no opportunity afforded for water having access from the exterior to the interior of the shoe through such air conductors.

Various modifications of our invention, within the scope of the appended claims, may be made without departing from its spirit.

Having thus described our invention, what we claim and desire to secure by Letters Patent is:—

1. In a shoe, the combination with the sole, of a circular member built in said sole and having one or more air passages communicating with the interior of the shoe through said sole, and having a screw threaded upper end, a spring located in and detachable from said member, and a foot supporting inverted cup shaped device resting upon said spring and having its lower end screw threaded and detachably fitted to

the threaded portion of the circular member, the side walls of said device being flexible.

2. In a shoe, the combination with the sole, of a cup shaped member embedded in said sole and having one or more air passages communicating with the interior of the shoe through the sole, and having a screw threaded upper end, of a spring located in said member, a screw threaded ring detachably fitted to the threaded upper end of the cup shaped member, a flexible tubular member having its lower end secured to said ring, and a foot support resting on said spring and secured to the upper end of said flexible member.

3. In a shoe, the combination with the sole, of a cup shaped member embedded in said sole above the heel of the shoe, and having a screw threaded upper end disposed below the upper side of the sole, and having one or more air passages communicating with the interior of the shoe through the sole, a coil spring located removably in said cup shaped member, a flexible tubular member, a foot support resting on the said spring and secured to the upper end of said flexible member, and two rings between which the lower end of the flexible member is clamped, one of said rings being screw threaded and detachably fitted to the threaded upper end of the cup shaped member.

In testimony whereof we have signed our names to this specification in presence of two subscribing witnesses.

ISAAC BERNAT.
CARL ROSS.
ADOLF BERNAT.
